BENJAMIN H. SMITH, OF TURTLE CREEK, PENNSYLVANIA, ASSIGNOR TO WESTINGHOUSE ELECTRIC AND MANUFACTURING COMPANY, A CORPORATION OF PENNSYLVANIA.

ELECTRICAL PROTECTIVE DEVICE.

1,204,510.

Specification of Letters Patent. Patented Nov. 14, 1916.

Application filed December 29, 1914. Serial No. 879,497.

To all whom it may concern:

Be it known that I, BENJAMIN H. SMITH, a citizen of the United States, and a resident of Turtle Creek, in the county of Allegheny and State of Pennsylvania, have invented a new and useful Improvement in Electrical Protective Devices, of which the following is a specification.

My invention relates to electrical protective devices and particularly to relay mechanisms that are employed for tripping circuit interrupters or other similar devices upon the occurrence of predetermined circuit conditions.

My invention has for its object to provide a device of the character above indicated that will operate correctly upon any value of overload.

My copending application, Serial #850,331, filed July 11, 1914, discloses a relay system that comprises a time-element relay which is adapted to control an auxiliary winding on a tripping electromagnet for the purpose of permitting the electromagnet to operate under predetermined conditions. With a device of this type, a circuit interrupter may be tripped by current derived from a circuit in connection with which the circuit interrupter is employed without subjecting the contact members of the relay to any injurious arcing or welding. However, when a device of this type is employed to interrupt very large currents, the tripping electromagnet will frequently operate irrespective of the auxiliary winding that is controlled by the relay.

In order to cause the tripping electromagnet to operate correctly for any value of current, I provide a two-part movable core member for the tripping electromagnet, one part of which is actuated upon excessive overloads and the other part, that actuates the latch, is operated in response to the control or auxiliary winding of the relay, thus providing a device that is operative for all values of current.

Figure 1 of the accompanying drawings diagrammatically illustrates a part of a system embodying my invention, and Fig. 2 is a detail illustration of a tripping electromagnet embodying my invention.

An alternating current circuit 1 is provided with an interrupter 2 for opening it under predetermined conditions. In order to trip the circuit interrupter 2, I provide

a relay system 3 that derives its energy from the circuit 1 through a current transformer 4 and a voltage transformer 5. The relay system 3 comprises a relay 6 that is of the induction type and is preferably constructed as set forth in application, Serial #497,799, filed May 22, 1909 and a tripping electromagnet 7. The secondary winding 8 of the transformer 5 is connected to the windings 9 and 10 of the relay 6, and the secondary winding 11 of the transformer 4 is connected in series relation to the winding 12 of the relay 6 and the windings 13 and 14 of the electromagnet 7. The relay 6 is provided with an armature 15 that is mounted on a shaft 16 which is provided with a contact arm 17. The contact arm 17 cooperates with a contact member 26 for the purpose of controlling the circuit of an auxiliary or controlling winding 18 of the electromagnet 7.

The electromagnet 7 comprises a stationary magnetizable core member 19 in the form of a hollow rectangle having a pole-piece 20 extending inwardly and downwardly from the upper cross-piece thereof and having a gap in the lower cross-piece through which projects a movable core member 21 that is adapted for longitudinal vertical movement. A substantially E-shaped portion 22 is mounted with its longer legs terminating adjacent to the lower end of the core member 19. The movable core member 21 normally rests upon the middle leg or pole piece of the core part 22, and, together with the said middle leg or pole piece, is surrounded by the windings 14 and 18. The movable core member 21 comprises two parts 23 and 24 that are relatively movable with respect to each other and are operatively connected together by a spring 25. The lower part 24 is connected to an operating rod 27 and the upper part 23 is loosely disposed about the rod 27, substantially as shown in Fig. 2 of the drawing.

As hereinbefore stated, the windings 13 and 14 are supplied with current from the secondary winding 11 of the transformer 4 and are preferably connected in series with the winding 12 of the relay 6, although they may be connected in any other suitable relation with respect thereto. The winding 18 is normally open-circuited but is adapted to be closed-circuited by the engagement of the contact members 17 and 26 of the relay.

6, under predetermined circuit conditions, such, for instance, as upon the occurrence of an overload or a reversal of the direction of flow of energy in the circuit 1. Under 5 normal circuit conditions, the current in the winding 12 of the relay 6 is insufficient to cause the switch 17-26 to close, and consequently, the winding 18 remains open-circuited and is not affected. However, the 10 windings 13 and 14 are continuously energized so long as the circuit interrupter 2 remains closed, but, being located upon opposite sides of the lower end cross-piece of the core member 19, and being also provided with separate magnetic circuits, they 15 exert opposing forces upon the core member 21. The magnetic circuit of the winding 14 being substantially closed, under normal conditions, the movable core member 21 20 remains stationary in the position shown. Also, since the magnetic circuit of the winding 14 is normally closed whereas, a considerable air gap exists in the magnetic circuit of the winding 13 at the upper end of 25 the movable core member 21, it is obvious that the winding 14 may, and preferably does, have a smaller number of convolutions than the winding 13.

When an overload or other abnormal condition occurs upon the circuit 1, an increased current is induced in the winding 11 of the transformer 4 which is sufficient to cause the relay 6 to close the switch 17-26, the closing of which may be delayed or not, as desired. When the switch 17-26 is closed, the winding 18 is closed-circuited and an electromotive force is induced by it in the winding 14, thereby decreasing the magnetizing effect of the winding 14 because of the 40 counter flux produced by the winding 18. When the magnetizing effect of the winding 14 is reduced, the pull exerted by the winding 13 is permitted to predominate over that of the winding 14, and the movable core 45 member 21 will rise in its entirety, thereby tripping the circuit interrupter 2. When the overload or other abnormal circuit conditions disappear or the circuit interrupter is opened, the switch 17-26 is opened, and the movable 50 core member 21 is returned by gravity to its normal position.

If the movable core member 21 were not composed of two relatively movable parts 23 and 24, when an excessive overload occurred 55 on the circuit 1, sufficient current would traverse the winding 13 to cause the movable core member 21 to operate irrespective of the operation of the relay 6. In order to avoid this condition, the movable core member 21 is composed of the two relatively 60 movable parts 23 and 24 that operate substantially as follows: When the excessive overload occurs, the part 23 is moved upwardly by the force of the current traversing the winding 13, and the part 24 is re-

tained in its initial position by the force incident to the current traversing the winding 14. After the relay 6 has operated to close the switch 17-26, the winding 18 is closed-circuited, thus weakening the effect of the winding 14 and permitting the spring 25 to draw the part 24 upwardly. Since the part 24 is connected to the rod 27, the upward movement of the same trips the circuit breaker 2, substantially as hereinbefore set forth.

While I have shown and described my invention in a preferred form, it may, obviously, be variously modified within the scope of the appended claims.

I claim as my invention:

1. An electromagnetic device comprising a stationary core member, a movable core member having two magnetizable portions, means for resiliently connecting the two portions together, two main windings for the movable core member adapted to move the two portions of the core member in opposite directions and an auxiliary winding for neutralizing the effect of one of the main windings under predetermined conditions.

2. An electromagnet comprising a stationary core member, a movable core member having two relatively movable magnetizable parts, a resilient member for operatively connecting the two parts together, two windings adapted to move the two parts of the core member in opposite directions, and means for neutralizing the effect of one of the said windings under predetermined conditions.

3. In a relay system, the combination with a relay, of an electromagnet comprising a stationary core member, a two-part movable core member, a spring for operatively connecting the two parts together, two windings adapted to produce opposing pulls upon the two parts of the movable core member and a third winding that is controlled by the said relay for neutralizing the effect of one of the said windings under predetermined conditions.

4. An electromagnetic device comprising a stationary core member, a two-part movable core member, means for resiliently connecting the two parts of the movable core member together, means tending to move the two parts of the core member in opposite directions and means for so neutralizing the said means that the two parts are permitted to move in the same direction under predetermined conditions.

5. An electromagnetic device comprising a stationary magnetizable core member having two magnetic paths, a two-part movable core member, a spring for connecting the two parts of the core member together, a winding for each of the magnetic paths tending to move the two parts of the core member in opposite directions, and a third

winding for decreasing the flux in one of the said magnetic paths to permit both parts of the movable core member to move in one direction.

5 6. An electromagnet comprising a movable core member having two relatively movable magnetizable parts resiliently connected together, a normally energized winding tending to move one part of the moving 10 core member in one direction, a second winding for preventing the movement of the other part of the movable core member in the direction that the first mentioned part is moved and means for neutralizing the 15 effect of the said second winding under predetermined conditions.

7. An electromagnet comprising two movable core members, means for resiliently connecting the same together, a normally 20 energized winding tending to actuate one of the said movable core members, and a second winding for preventing the actuation of the other movable core member and a third winding for neutralizing the effect of 25 the said second winding under predetermined conditions.

8. An electromagnet comprising two movable core parts, a tripping rod operatively connected to one of the said core parts the 30 other core part being loosely disposed about the said rod, a spring for operatively connecting the two core parts together, a winding tending to actuate the loosely disposed core part, and a second winding adapted to 35 prevent the actuation of the core part that is attached to the said rod except under predetermined conditions.

9. An electromagnet comprising two movable core members, a spring for operatively 40 connecting the core members together, a rod operatively connected to one of the core members, means tending to move the said core members in opposite directions, and means for permitting the said core member 45 that is operatively connected to the rod to move in the same direction as the other core member under predetermined conditions.

10. An electromagnetic device comprising a stationary core member, two movable magnetizable core members therefor, a spring 50 operatively connected between the movable core members, means tending to move the core members in opposite directions and means for causing the movable core members to move in one direction under predetermined conditions.

11. An electromagnet comprising two

movable core members, a spring operatively connected between the movable core members, a winding tending to move the core 60 members in opposite directions and means for causing the movable core members to move in one direction under predetermined conditions.

12. The combination with an electric circuit and a relay having an actuating winding, of an electromagnet comprising a stationary core member, a two-part movable core member, means for resiliently connecting the two parts of the movable core member together, means connected in series with the relay winding tending to move the two parts of the core member in opposite directions, and means controlled by the relay for so neutralizing the said means for actuating the movable core member that the two parts are permitted to move in the same direction.

13. The combination with an electric circuit and a relay having an actuating winding, of an electromagnet comprising a stationary core member, a two-part movable core member, means for resiliently connecting the two parts of the movable core member together, means connected in series with 80 the relay winding tending to move the two parts of the core member in opposite directions, and a normally open-circuited winding adapted to be closed-circuited by the relay for neutralizing the said means for 85 actuating the movable core member under 90 predetermined conditions.

14. The combination with an electric circuit and a relay having an actuating winding, of an electromagnet comprising a stationary core member, a two-part movable core member, means for resiliently connecting the two parts of the movable core member together, a main winding connected in series with the relay winding for tending 95 to move the two parts of the core member in opposite directions, and a normally open-circuited winding adapted to be closed-circuited by the relay for neutralizing the effect of the main winding on one part of 100 the movable core member under predetermined conditions.

In testimony whereof, I have hereunto subscribed my name this 22nd day of Dec. 1914.

BENJAMIN H. SMITH.
